(57) **CLAIM**

The ornamental design for a temperature indicator, as shown and described.

DESCRIPTION

FIG. 1 is an illustration of a front view of a first embodiment of the invention;
FIG. 2 is an illustration of an isometric view of the embodiment of the invention shown in FIG. 1;

FIG. 3 is an illustration of an isometric view of the embodiment of the invention shown in FIG. 1;

FIG. 4 is an illustration of an isometric view of the embodiment of the invention shown in FIG. 1;

FIG. 5 is an illustration of an isometric view of the embodiment of the invention shown in FIG. 1;

FIG. 6 is an illustration of a front view of a second embodiment of the invention;

FIG. 7 is an illustration of an isometric view of the embodiment of the invention shown in FIG. 6;

FIG. 8 is an illustration of an isometric view of the embodiment of the invention shown in FIG. 6;

FIG. 9 is an illustration of an isometric view of the embodiment of the invention shown in FIG. 6;

FIG. 10 is an illustration of an isometric view of the embodiment of the invention shown in FIG. 6;

FIG. 11 is an illustration of a front view of a third embodiment of the invention;

FIG. 12 is an illustration of an isometric view of the embodiment of the invention shown in FIG. 11;

FIG. 13 is an illustration of an isometric view of the embodiment of the invention shown in FIG. 11;

FIG. 14 is an illustration of an isometric view of the embodiment of the invention shown in FIG. 11;

FIG. 15 is an illustration of an isometric view of the embodiment of the invention shown in FIG. 11;

FIG. 16 is an illustration of a front view of a fourth embodiment of the invention;

FIG. 17 is an illustration of an isometric view of the embodiment of the invention shown in FIG. 16;

FIG. 18 is an illustration of an isometric view of the embodiment of the invention shown in FIG. 16;

FIG. 19 is an illustration of an isometric view of the embodiment of the invention shown in FIG. 16;

FIG. 20 is an illustration of an isometric view of the embodiment of the invention shown in FIG. 16;

FIG. 21 is an illustration of a left edge view of the embodiments of the invention shown in FIGS. 1, 6, 11, and 16;

(Continued)

FIG. 22 is an illustration of a right edge view of the embodiments of the invention shown in FIGS. 1, 6, 11, and 16;

FIG. 23 is an illustration of a rear view of the embodiments of the invention shown in FIGS. 1 and 6;

FIG. 24 is an illustration of a top edge view of the embodiments of the invention shown in FIGS. 1, 6, 11, and 16;

FIG. 25 is an illustration of a bottom edge view of the embodiments of the invention shown in FIGS. 1, 6, 11, and 16;

FIG. 26 is an illustration of a rear view of the embodiments of the invention shown in FIGS. 11 and 16;

FIG. 27 is an illustration of the embodiment of the invention shown in FIG. 1;

FIG. 28 is an illustration of the embodiment of the invention shown in FIG. 6;

FIG. 29 is an illustration of the embodiment of the invention shown in FIG. 11;

FIG. 30 is an illustration of the embodiment of the invention shown in FIG. 16; and,

Figure drawings 2-5, 7-10, 12-15 and 17-20 disclose the claimed design is use.

Broken lines in the disclosure are understood to be for illustrative purposes only and form no part of the claimed design.
